SLIDER FOR SLIDE FASTENERS

Noel J. Poux, Meadville, Pa., assignor to Talon,
Inc., a corporation of Pennsylvania

Application August 12, 1950, Serial No. 179,038

3 Claims. (Cl. 24—205.14)

1

This invention relates to slide fasteners, and particularly to an improvement in or a modification of the type of automatic lock slider described and claimed in the patent to Norton et al., No. 1,966,457, issued July 17, 1934.

The lock slider of the above mentioned patent has been used successfully for many years and is satisfactory for most purposes. In some applications of the fastener, however, for example in garments, a pendant or other decorative or ornamental device is oftentimes attached to the pull of the slider so as to be suspended therefrom. Such a pendant or device is sometimes relatively heavy and the weight thereof in such suspended position tends to move by a camming action the locking member to its unlocked position thereby causing the slider to be moved unintentionally along the fastener to open the same. Naturally, such a condition is undesirable for it defeats the purpose for which the lock on the slider is intended. It is to a means for preventing such accidental unlocking of the slider that the present invention relates.

Accordingly, it is the general object of this invention to provide an improved lock slider which, while retaining all of the advantages and functions of the slider of the Norton et al. patent, will overcome the above mentioned difficulty.

It is a more specific object of the present invention to provide means incorporated with the aforementioned automatic lock slider which will function to hold the pull member in a suspended position out of operable engagement with the locking member whenever the pull is released.

It is another object of the invention to provide an improved automatic lock slider having means incorporated therewith for overcoming the aforementioned difficulty in a simple and effective manner, and yet which will not add materially to the cost of manufacture thereof.

Various other objects and advantages of this invention will be more apparent in the course of the following specification, and will be particularly pointed out in the appended claims.

In the accompanying drawings, there is shown for the purpose of illustration, an embodiment which my invention may assume in practice.

In these drawings:

Fig. 1 is a plan view of a slide fastener having a slider with my improvement incorporated therewith;

Fig. 2 is a side view of the fastener, as shown in Fig. 1;

Fig. 3 is a sectional view taken on line 3—3 of Fig. 1;

2

Fig. 4 is a sectional view taken on line 4—4 of Fig. 1;

Fig. 5 is a sectional view taken on line 5—5 of Fig. 1;

Fig. 6 is a plan view of the slider body with the locking member and pull removed; and

Fig. 7 is a side view of the fastener, similar to Fig. 2, showing the locking member in its unlocked position.

Referring more particularly to the drawings, my improvement is shown illustrated with a conventional type slide fastener of the type disclosed in the aforesaid Norton et al. patent, having a pair of stringer tapes 2 with a series of spaced-apart interlocking fastener elements 3 attached to their adjacent edges. A slider body 4 is provided for longitudinal movement along the fastener for opening and closing the same, and comprises spaced-apart upper and lower wings or plates 5 and 6, respectively, having flanges 7 along their marginal edges and connected together at one end by a neck portion 8 so as to provide a Y-shaped channel 9 between the wings 5 and 6 through which the fastener elements are guided when the slider is manipulated to open or close the fastener.

On the outer side of the upper wing, there is arranged an elongated lug 10 upon which there is mounted a hollow sheet metal locking member 12 in the form of a cap which fits over and around the lug and has a top wall and side walls 13 and 14 and preferably end walls. This locking member is pivotally attached to the lug 10 at the upper end thereof, as at 15, preferably by projections on the inner surfaces of the side walls which extend into indentations in the opposed side surfaces of the lug. In the top surface of the lug there is anchored therein, a leaf spring 18 which extends over the lug to the other side of the pivotal connection 15, with the extreme free end thereof bearing against the inner surface of the top wall of the locking member beyond the pivotal connection. On the free end of the locking member or that end opposite that from the pivotal connection, there is carried by the side wall 13, a locking projection or prong 19 which is preferably an extension of this side wall. This locking prong extends normally into and through an opening 20 in the top wing 5 of the slider body into the channel 9 thereof due to the action of the spring 18 which urges the locking prong into locking position between any adjacent pair of fastener elements 3 in a well-known manner, as shown in Figs. 2, 3, and 4.

There is provided a pull tab 21 which may be

of a convenient form and, in the present instance, this pull tab is shown as being substantially U-shaped having inwardly extending trunnion portions 22 and 23 which fit loosely in under the lower edges of the side walls 13 and 14 of the locking member so as to embrace the same and so as to be disposed to either side of the lug 10 and movable relative to both the locking member and the lug. This pull tab is provided to manipulate the slider and when so used to open the fastener the trunnions engage an inclined surface 24 on the inner side of the locking prong 19 of the side wall 13, as shown in Fig. 7, thereby moving the locking prong out of engagement with the fastener elements.

According to the present invention, there is carried by the pull tab 21 adjacent each of the trunnion portions 22 and 23 thereof, hook-like projecting portions 25 and 26, respectively, which are adapted to extend normally into corresponding openings 27 and 28, respectively, in the top wing of the slider body with one arranged to either side of the lug 10, as shown in Fig. 6. These projecting portions are adapted to hook over the lower edge of the openings 27 and 28, as shown in Figs. 2 and 5, when the pull tab is released so as to hold the pull tab and the pendant 29 or other decorative device attached thereto in a suspended position with the trunnion portions out of engagement with the inclined surface 24 of the side wall of the locking member thereby preventing the weight of the pendant from operating on the locking member tending to move the locking member out of its locked position. It will be understood that the bottom sides of the openings 27 and 28 are positioned a distance from the locking prong 19 just sufficient to keep the trunnion from contacting the inclined surface 24 when the projections 25 and 26 are positioned in their corresponding openings 27 and 28 so that the trunnions cannot act to tend to move the locking member to its unlocked position. It will be seen that the lower edge of the side walls 13 and 14 of the locking member tends to urge and hold the projections 25 and 26 into their corresponding openings 27 and 28 due to the action of the spring 18 when the pull tab is released, as shown in Fig. 2.

In operation when the fastener is being opened, the pull tab will be disposed, as shown in Fig. 7 of the drawings, with the slider being moved downwardly. In such position, it will be seen that the pull tab is raised slightly upwardly out of parallelism with the slider body so as to be disposed at a slight angle thereto. In moving the pull tab to such position, the projections 25 and 26 are moved out of their corresponding openings 27 and 28 so as to permit the trunnion portion of the pull tab to engage the inclined surface 24 of the locking member thereby moving it out of engagement with the fastener elements. It is maintained in such position until the pull tab is released and it again assumes its locked position, as shown in Fig. 2.

As a result of my invention, it will be seen that there is provided a simple and inexpensive means for effectively holding the pull tab in a suspended position out of contact with the locking member when the locking member is in its locked position thereby eliminating any danger of accidental downward movement of the slider along the fastener elements in an opening direction.

While I have shown and described an embodiment which my invention may assume in

practice, it will be understood that this embodiment is merely for the purpose of illustration and description, and that other forms may be devised within the scope of my invention as defined in the appended claims.

What I claim as my invention is:

1. A slider for slide fasteners of the class described, comprising a slider body, a lug projecting from one side of said slider body, a locking member pivotally connected to said lug at one end and having a locking projection on its other end, a pull member connected to said slider body for longitudinal movement therealong having trunnion portions engageable with said locking member for moving the same to its unlocked position when a pulling force is exerted to said pull member, resilient means for normally urging said locking member to locked position when the pull member is released, and a projection extending outwardly from the face of said pull member adjacent the trunnion portions thereof, said slider body having an aperture in the wing thereof into which said projection is adapted to extend when the pull member is disposed in a suspended and locked position, said projection adapted to rest on the lower wall of said aperture so that the weight of said pull member or any member attached thereto will not tend to move the locking member to its unlocked position.
2. A slider for slide fasteners of the class described, comprising a slider body, a lug projecting from one side of said slider body, a locking member pivotally connected to said lug at one end and having a locking projection on its other end, a pull member connected to said slider body for longitudinal movement therealong having trunnion portions engageable with said locking member for moving the same to its unlocked position when a pulling force is exerted to said pull member, resilient means for normally urging said locking member to locked position when the pull member is released, and a pair of projections extending outwardly from the trunnion portions of said pull member, said slider body having a pair of apertures in the wing thereof into which said projections are adapted to extend when the pull member is disposed in a suspended and locked position, said projections adapted to rest on the lower wall of the respective aperture so that the weight of said pull member or any member attached thereto will not tend to move the locking member to its unlocked position.
3. A slider for slide fasteners of the class described, as defined in claim 1, including means carried by the locking member tending to force automatically the projections into the apertures by the action of the locking member.
